VISIBLE INDEX EMBODYING A PLURALITY
OF SWINGABLE PANELSMarchand B. Hall, Chicago, Ill., assignor to Acme
Visible Records, Inc., Chicago, Ill., a corpora-
tion of Delaware

Application December 15, 1947, Serial No. 791,908

9 Claims. (Cl. 40—102)

1

This invention relates to improvements in visible indexes, and is more particularly concerned with the provision of a relatively small compact desk size unit embodying a plurality of swingable panels adapted to bear written or printed matter, such as names, addresses, telephone numbers, etc.

It is an object of the present invention to provide a visible index embodying a pair of mounting plates projecting upwardly in spaced parallel relation from a suitable base and having their upper edges recessed at equally spaced intervals to receive the ends of resilient hanger wires, said mounting plates being formed with abutment flanges at the entrance to said recesses to hold their respective hanger wires against outward displacement.

It is a further object of this invention to provide the mounting plates with recesses and abutment flanges which permit mounting or removal of resilient hanger wires from their respective recesses by bending the hanger wires into bow-shape.

It is a further object of this invention to mount a plurality of panels upon each hanger wire by means of clips.

This invention embodies other novel features, details of construction and arrangement of parts which are hereinafter set forth in the specification and claims and illustrated in the accompanying drawings, wherein:

Fig. 1 is a top plan view showing a visible index embodying features of this invention, the hanger wires and associated panels being removed from the index.

Fig. 2 is a longitudinal sectional view taken along the line 2—2 of Fig. 1.

Fig. 3 is an enlarged fragmentary sectional view taken along the line 3—3 of Fig. 1.

Fig. 4 is an enlarged fragmentary plan view illustrating that portion of the index shown in Fig. 3.

Fig. 5 is a perspective view illustrating the index and the manner of mounting same upon a supporting platform.

Fig. 6 is a perspective view illustrating the manner of mounting a plurality of panels upon a common hinge wire.

Fig. 7 is a detail sectional view taken along the line 7—7 of Fig. 6.

Referring now to the drawings for a better understanding of this invention, the visible index is shown as comprising a base 6 formed with side walls 7—7 and a back wall 8. A pair of mounting plates 9—9 project upwardly in spaced paral-

lel relation from the base 6 and adjacent the inner sides of the side walls 7—7. The base 6 and mounting plates 9—9 are preferably formed from sheet metal, the mounting plates 9—9 being secured to the base by means of spot-welding or other fastening means.

As viewed in side elevation, the upper edges of the mounting plates 9—9 incline upwardly toward the back wall 8 and are formed with a plurality of equally spaced recesses 11 which are rounded at their inner ends to define seat portions 12 to snugly receive the ends of resilient hanger wires 13. The upper edges of the mounting plates 9—9 are formed with a plurality of abutment flanges 14 defining one side of the entrance to the recesses 11. The abutment flanges 14 are bent outwardly at an angle to the plane of the respective mounting plates and serve to prevent movement of a straight hanger wire into or out of the recesses 11 when the hanger wire is disposed in a plane normal to the mounting plates. The hanger wires 13 are inserted into or removed from the recesses 11 by manually bending the hanger wires into bow-shape, as illustrated in Fig. 4 in the drawings. After the hanger wire is mounted in the seat portion 12 of its recesses 11, it assumes its normal straight shape and is held against outward displacement by means of the abutment shoulders 14. It will be noted that the side walls 7—7 serve to prevent axial displacement of the hanger wires relative to the mounting plates 9—9.

Bearing apertures are provided in the upper rear corners of the mounting plates 9—9 to receive a mounting pin 16 which serves as a journal for a clip 17 spot-welded to a cover 18. The cover 18 is preferably formed of metal and has its side edges 19—19 bent inwardly to define a pair of opposing recesses to receive the side edges 40 of a card 21. The card 21 is adapted to bear any suitable printed or written matter and may be replaced, when desired, by a new card. The cover 18 is supported in its open upright position by means of a flange 22 provided at the upper end 45 of the back wall 8.

A pair of metal plates 23—23 are spot-welded or otherwise secured to the base 6 and have their outer edges bent outwardly and thence inwardly at 24—24 to provide a pair of opposing recesses 50 to receive and engage the side edges of a sheet of cardboard or the like.

A cross-strip 26 is welded at its ends to the upper surfaces of the metal plates 23—23 and defines, with the upper surface of the base 6, an elongated recess 55 to receive a tongue 28 pro-

vided on a mounting plate 29. A metal plate 31 is secured to the back end of the mounting plate 29 and is formed with a back wall 32 and side walls 33—33 to snugly receive and engage the adjacent portions of the back wall 8 and side walls 9—9 of the base 6. The supporting plate 29 is adapted to be secured to the upper surface of a desk, table or the like by means of screws. The base 6 is removed from the mounting plate 29 by merely lifting same upwardly and thence rearwardly.

Three or more panels, indicated at A, B and C, in Fig. 6 of the drawings, are adapted to be pivotally connected to each hanger wire 13 by means of metal clips generally indicated at 36; the metal clips 36 are formed from strip material bent intermediate their ends to provide leg portions 37 and 38 and a connecting loop portion 39 to receive the hanger wire 13. The outer end of the leg portion 37 is bent inwardly at 41 to project through the thickness of its respective panel. By referring to Fig. 6, it will be noted that each panel is provided with two clips for engagement with a hanger wire.

One of the most important features of the present invention resides in the provision of a simple and inexpensive means for mounting resilient hanger wires for use in a visible index. It will be noted that the hanger wires, and their respective panels, are readily positioned within their respective recesses 11 by merely bending the resilient hanger wire into bow-shape; after which, the end portions of the hanger wire are held against outward displacement by means of their respective abutment flanges 14. It will also be noted that the several panels may readily be removed from the visible index by bending the hanger wire into bow-shape; after which, the panels may be removed from their hanger wire to facilitate applying written or printed data thereto. By providing opposing recesses along the side walls of the cover 18, by means of the flanges 19—19, a suitable card bearing printed or written matter may be demountably positioned upon the cover 18. Another demountable card, not shown, bearing suitable written or printed matter may be positioned in the opposing recesses defined by the inturned flanges 24—24 of the plates 23—23.

While this invention has been shown in but one form, it is obvious to those skilled in the art that it is not so limited but is susceptible of various changes and modifications without departing from the spirit and scope of the claimed invention.

I claim as my invention:

1. In a visible index adapted to receive a hanger wire, a base, a pair of mounting plates projecting upwardly in spaced parallel relation from said base, said mounting plates being formed with recesses in their upper edges, the inner end of each recess having walls defining a seat portion to receive the end of a straight hanger wire disposed in a plane normal to the mounting plates, an abutment flange provided at the entrance to each recess to engage and hold the end of a straight hanger wire against displacement from its respective seat portion, said abutment flange projecting outwardly at an angle from the plane of its respective mounting plate.

2. In a visible index adapted to receive a hanger wire, a base, a pair of mounting plates projecting upwardly in spaced parallel relation from said base, said mounting plates being formed with recesses in their upper edges, the inner end of each recess having walls defining a seat por-

tion to receive the end of a straight hanger wire disposed in a plane normal to the mounting plates, an abutment flange provided at the entrance to each recess to engage and hold the end of a straight hanger wire against displacement from its respective seat portion, said abutment flange projecting outwardly at an angle from the plane of its respective mounting plate, the free edge of said abutment flange defining one wall of the entrance to said recess.

3. In a visible index adapted to receive a hanger wire, a base, a pair of mounting plates projecting upwardly in spaced parallel relation from said base, said mounting plates being formed with recesses in their upper edges, the inner end of each recess having walls defining a seat portion to receive the end of a straight hanger wire disposed in a plane normal to the mounting plates, an abutment flange provided at the entrance to each recess to engage and hold the end of a straight hanger wire against displacement from its respective seat portion, said abutment flange projecting outwardly at an angle from the plane of its respective mounting plate, the free edge of said abutment flange defining one wall of the entrance to said recess.

15 4. In a visible index adapted to receive a hanger wire, a base, a pair of mounting plates projecting upwardly in spaced parallel relation from said base, said mounting plates being formed with recesses in their upper edges, the inner end of each recess having walls defining a seat portion to receive the end of a straight hanger wire disposed in a plane normal to the mounting plates, an abutment flange provided at the entrance to each recess to engage and hold the end of a straight hanger wire against displacement from its respective seat portion, said abutment flange projecting outwardly at an angle from the plane of its respective mounting plate, the free edge of said abutment flange defining one wall of the entrance to said recess, side walls provided along the side edges of said base and adjacent the outer sides of said mounting plates to prevent axial displacement of a hanger mounted in said recesses.

30 5. In a visible index adapted to receive a hanger wire, a base, a pair of mounting plates projecting upwardly in spaced parallel relation from said base, said mounting plates being formed with recesses in their upper edges, the inner end of each recess having walls defining a seat portion to receive the end of a straight hanger wire disposed in a plane normal to the mounting plates, an abutment flange provided at the entrance to each recess to engage and hold the end of a straight hanger wire against displacement from its respective seat portion, said abutment flange projecting outwardly at an angle from the plane of its respective mounting plate, the free edge of said abutment flange defining one wall of the entrance to said recess, side walls provided along the side edges of said base and adjacent the outer sides of said mounting plates to prevent axial displacement of a hanger from said recesses.

35 6. In a visible index adapted to receive a hanger wire, a base, a pair of mounting plates projecting upwardly in spaced parallel relation from said base, said mounting plates being formed with recesses in their upper edges, the inner end of each recess having walls defining a seat portion to receive the end of a straight hanger wire disposed in a plane normal to the mounting plates, an abutment flange provided at the entrance to each recess to engage and hold the end of a straight hanger wire against displacement from its respective seat portion, said abutment flange projecting outwardly at an angle from the plane of its respective mounting plate, the free edge of said abutment flange defining one wall of the entrance to said recess, side walls provided along the side edges of said base and adjacent the outer sides of said mounting plates to prevent axial displacement of a hanger from said recesses, said mounting plates being formed with bearing apertures, and a cover journaled in said bearing apertures.

40 7. In a visible index adapted to receive a hanger wire, a base, a pair of mounting plates projecting upwardly in spaced parallel relation from said base, said mounting plates being formed with recesses in their upper edges, the inner end of each recess having walls defining a seat portion to receive the end of a straight hanger wire dis-

posed in a plane normal to the mounting plates, an abutment flange provided at the entrance to each recess to engage and hold the end of a straight hanger wire against displacement from its respective seat portion, said abutment flange projecting outwardly at an angle from the plane of its respective mounting plate, the free edge of said abutment flange defining one wall of the entrance to said recess, side walls provided along the side edges of said base and adjacent the outer sides of said mounting plates to prevent axial displacement of a hanger from said recesses, said mounting plates being formed with bearing apertures, a cover journaled in said bearing apertures, and a back wall projecting upwardly from said base and disposed to support said cover in its open position.

7. In a visible index, a base, side walls extending upwardly in spaced parallel relation from said base, a pair of mounting plates disposed in spaced parallel relation upon said base and adjacent the inner sides of said side walls, said mounting plates being formed with recesses in their upper edges, the inner ends of each recess having walls defining a seat portion, a resilient hanger wire mounted in the seat portions formed in said mounting plates, an abutment flange provided at the entrance to each recess to hold said hanger wire against upward displacement from its respective seat portion, said abutment flanges projecting outwardly at an angle from the plane of its respective mounting plate.

8. In a visible index, a base, side walls extending upwardly in spaced parallel relation from said base, a pair of mounting plates disposed in spaced parallel relation upon said base and adjacent the inner sides of said side walls, said mounting plates being formed with recesses in their upper edges, the inner ends of each recess having walls defining a seat portion, a resilient hanger wire mounted in the seat portions formed in

said mounting plates, an abutment flange provided at the entrance to each recess to hold said hanger wire against upward displacement from its respective seat portion, said abutment flanges projecting outwardly at an angle from the plane of its respective mounting plate, the free edge of each abutment flange defining one wall of the entrance leading to the seat portion of its respective recess.

9. In a visible index, a base, side walls extending upwardly in spaced parallel relation from said base, a pair of mounting plates disposed in spaced parallel relation upon said base and adjacent the inner sides of said side walls, said mounting plates being formed with recesses in their upper edges, the inner ends of each recess having walls defining a seat portion, a resilient hanger wire mounted in the seat portions formed in said mounting plates, an abutment flange provided at the entrance to each recess to hold said hanger wire against upward displacement from its respective seat portion, said abutment flanges projecting outwardly at an angle from the plane of its respective mounting plate, the free edge of each abutment flange defining one wall of the entrance leading to the seat portion of its respective recess, and a mounting plate for detachable engagement with said base.
